CLAIM

The ornamental design for an infusion pump as shown and described.

DESCRIPTION

FIG. 1 illustrates a perspective view of an infusion pump, according to our invention.

FIG. 2 illustrates a front view of the infusion pump shown in FIG. 1.

FIG. 3 illustrates a right side view of the infusion pump shown in FIG. 1.

FIG. 4 illustrates a left side view of the infusion pump shown in FIG. 1.

FIG. 5 illustrates a rear view of the infusion pump shown in FIG. 1.

FIG. 6 illustrates a top view of the infusion pump shown in FIG. 1; and,

FIG. 7 illustrates a bottom view of the infusion pump shown in FIG. 1.

The ornamental design that is claimed is shown in solid lines in the drawings. The broken lines in the drawings depict portions of the infusion pump that form no part of the claimed design.

1 Claim, 7 Drawing Sheets
